SUCTION CLEANER OUTLET CONSTRUCTION

Elmer J. Kasper, Cleveland, Ohio, assignor to The
P. A. Geler Company, Cleveland, Ohio, a cor-
poration of Ohio

Application March 13, 1939, Serial No. 261,475

1 Claim. (Cl. 230—132)

My invention relates to suction cleaner outlet construction and more particularly to outlet construction for portable tank type suction cleaners. When a usual portable tank type suction cleaner is operating, a disturbing whirring noise is created as the air is sucked through the cleaner by the action of its rapidly rotating fan.

It has not been commercially feasible to streamline the various ducts, compartments, fan or fans and the other interior parts of a usual tank type suction cleaner which the air contacts as it passes therethrough.

A suction cleaner having completely streamlined all its parts contacting the air would probably be relatively quiet in operation, but the cost of such a cleaner if desired would presumably be prohibitive.

On the other hand, there has existed the problem of reducing the noise of operation of tank type suction cleaners which are adapted for commercial production and sale.

The objects of the present improvements include the provision of an improved outlet construction for suction cleaners by the use of which a reduction of the operating noise is attained in a suction cleaner without altering the conformation of the other interior parts of the cleaner which contact the air passing therethrough.

Further objects of the present improvements include the provision of an outlet construction for suction cleaners which reduces the operating noise thereof without reducing its efficiency.

The foregoing and other objects are attained by the suction cleaner, suction cleaner outlet construction, parts, combinations, and sub-combinations, which comprise the present invention, and the nature of which is set forth in the following general statement, and preferred embodiments of which are set forth in the following description, and which are particularly and distinctly pointed out and set forth in the appended claims forming part hereof.

The nature of the improved suction cleaner and suction cleaner outlet construction of the present invention may be stated in general terms as including preferably in a tank type suction cleaner which may have either a horizontal, vertical or otherwise directed longitudinal axis of its tank and rotation of its fan or fans, a tank or housing in which the filter, fan, motor, and other usual parts of a suction cleaner are operatively arranged, the tank having an inlet opening and various orifices and openings in its interior walls through which the air passes, and having an outlet opening, and an improved outlet

construction preferably including a first tubular neck, which may be adapted for connection with blower appliances and the like, the inner end of the neck being connected with the outlet opening of the tank, and the outer end of the first tubular neck having a radially inwardly extending annular air stop flange with a central opening of less or reduced area than the outlet opening of the tank, and a second relatively short tubular neck having its inner end connected with the reduced opening of the flange, the second tubular neck having a wall which is internally convexly curved or rounded forming an interior convexly curved annular shoulder between the stop flange and the outer extremity opening of the second neck.

The minimum transverse outlet area of the second neck is preferably not less than the area of the minimum opening in the suction cleaner preceding the improved outlet through which the air passes.

By way of example, embodiments of the improved suction cleaner and the suction cleaner outlet construction of the present invention are illustrated in the accompanying drawing forming part hereof, in which

Figure 1 is a side elevation of a tank type suction cleaner, including the present improved outlet construction, with a fragmentary showing of the suction intake tube thereof, and the electric power supply line thereof, the longitudinal axis of the tank and the general direction of air flow therethrough being at a slight angle with the horizontal, and which for purposes of convenience of reference hereinafter may be termed a horizontal tank type suction cleaner;

Fig. 2, an enlarged fragmentary view thereof with portions broken away and shown in vertical section on the longitudinal axis of the cleaner, and other interior portions of the cleaner being shown in elevation;

Fig. 3, a fragmentary end elevation of the improved outlet construction looking in the direction of the arrows 3—3 Fig. 2; and

Fig. 4, an enlarged fragmentary view of the outlet end portions of Fig. 3, more clearly showing the details of the improved outlet construction.

Similar numerals refer to similar parts throughout the drawing.

In Figs. 1 to 4 inclusive there are illustrated a horizontal tank type suction cleaner indicated generally by 11, and including embodiments of the present improved outlet construction, in addition to other improvements which are not the

subject matter of the present invention, together with other usual parts of a tank type suction cleaner.

The horizontal tank type suction cleaner 11 includes as illustrated an elongated cylindric central filtering means housing tube 12 upon one end 13 of which a reducing flange cap 14 is mounted.

The larger end 15 of the reducing flange cap 14 fits over the end 13 of the central tube 12 and is separably secured thereon as by clasps 16; and the smaller outer end 17 of the reducing cap 14 separably receives a sleeve coupling 18 of a flexible suction intake tube 19.

Upon the other end 20 of the central tube 12 there is separably secured a motor driven fan unit indicated generally by 21, and the outer end of the fan unit 21 has removably secured thereon a convexly curved outlet cap indicated generally by 22.

Runner rod supports 23, one for each side of the cleaner have opposite ends secured as by screws to the central tube 12 and the fan unit 21. A carrying handle indicated generally by 24 likewise has its opposite ends secured to the central tube 12 and the fan unit 21. An electric supply flexible cable 25 is associated with a control switch indicated generally by 26 and with preferable electric motor 27 of the fan unit 21 in an operative manner not necessary for the purposes of the present improvements to be described in detail.

The motor driven fan unit 21, includes in addition to the motor 27, other parts all located within the interior of a preferably cylindric tube 28, which as shown is part of a one piece cup having a perforated transverse wall 29 extending across the extremity of its intake end 30 telescoped within the outlet end 31 of the central tube 12. Within the central tube 12 there is located filter bag means indicated generally by 32.

The motor 27 is located within the tube 28 and includes a frame indicated generally by 33 having an apertured circular flange 34 extending transversely across the interior of the tube 28, and from opposite sides of the circular flange 34 other parts of the motor frame extend, and mount the various parts of the motor including the shaft having the fan mounting end 35 which is coaxial with the longitudinal axis 36 of the alined motor housing tube 28 and central filtering means housing tube 12.

An inner fan tube 37 has one end secured as by screws 38 to the circular flange 34 and its other end provided with a wide inwardly extending annular flange wall 39.

Longitudinally spaced from the wide annular flange 39 towards the intake perforated wall 29 there is located a circular baffle wall 40 and between the wide annular flange wall 39 and the circular baffle wall 40 there are interposed a plurality of angled deflector vanes 41. The fan tube 37 is provided with an extension fan tube 42, one end of which is telescoped as shown over the intake end of the fan tube 37 having the inwardly extending transverse annular flange 39 thereon.

The extension fan tube 42 extends over the circular baffle wall 40 and is provided at its end adjacent the perforated intake wall 29 of the outer tube 28 with a wide inwardly extending annular flange wall 43.

A preferably resilient mounting ring 45 having an L-shaped cross section is interposed be-

tween the interior circular corner of the tube 28 and the intake wall 29 and the exterior circular corner of the tube 42 and the flange wall 43.

An improved peripherally apertured transverse baffle wall indicated generally by 44 is interposed between the motor frame 33 and the inwardly extending wide annular flange 39. The fan mounting end 35 of the motor shaft extends towards the perforated intake wall 29 through central apertures of the baffle wall 44, the wide annular flange wall 39, and the baffle wall 40.

A first fan compartment 46 is formed within the extension tube 42 between the wide annular flange wall 43 and the baffle wall 40; and a second fan compartment 47 is formed within the fan tube 37 between the wide annular flange wall 39 and the improved baffle wall 44.

A centrifugal fan indicated generally by 48 is located within the first fan compartment 46, and as shown another centrifugal fan indicated generally by 49 is located within the second fan compartment 47; and the fans 48 are removably secured to the fan mounting end 35 of the motor shaft as by cooperating nut clamped collar and spacer collar means indicated generally by 50.

Improved apertured baffle cup means indicated generally by 51 are telescoped within the discharge extremity 52 of the outer tube 28, and as shown there may be a resilient motor support pyramid indicated generally by 53 interposed between a central pyramidal portion 54 of the cup 51 and an adjacent cylindrical end 55 of the motor frame 33.

A filter fabric wall 56 may be as shown interposed between the interior of the outlet cap 22 and the flange cup 51. The outlet cap 22 is provided with a central reduced outlet neck opening 57.

The centrifugal fans 48 as shown are identical in construction and each includes a discharge side disk 58 having a central aperture 59 fitting on the fan mounting end 35 of the motor shaft, an intake side annular disk 60 having a central intake opening 61, and preferably curved fan blades 62 interposed between the disks 58 and 60.

The intake opening 61 of the fan 48 of the first fan compartment 46, as shown, is adjacent and registers with the opening 43-1 of the wide transverse flange wall 43; and the intake opening 61 of the fan 49 in the second fan compartment 47 as shown registers with the adjacent opening 63 of the wide flange wall 39.

In the present improved outlet construction indicated generally by 64, the outlet neck opening 57 of the outlet cap 22 connects with the inner end of a first tubular neck 65, and in usual outlet construction the outer end of the neck 65 would terminate as the extreme outlet opening of the suction cleaner 11.

In the improved outlet construction however from the outer end of the first tubular neck 65 there extends radially inwardly an annular air stop flange 66 having a central opening 67 of less or reduced area than the area of the outlet opening 57 of the outlet cap 22.

A second relatively short tubular neck 68 has its inner end connected with the reduced opening 67 of the stop flange 66 and the second tubular neck for the purposes of the present improvements has a wall 69 which is interiorly convexly curved or rounded to form an interiorly convexly curved annular shoulder between the stop flange 66 and the outer extremity opening 70 of the second neck 68.

The minimum transverse outlet area of the

second neck 68, which as shown is the area of the outer extremity opening 70, is preferably not less than the area of the minimum opening in the suction cleaner 11 preceding the improved outlet 64 through which the air passes.

In the suction cleaner 11, the inlet flange cap 14, the tube 12, the tube 28, and the outlet cap 22 constitute the tank of the cleaner, and the outlet opening 57 may thus be termed the outlet opening 57 of the cleaner tank, which is connected with the inner end of the improved outlet construction 64.

In operation, in the improved suction cleaner 11 with the improved outlet construction 64, the use of the stop flange 66 with its outlet opening 67 of less area than the normal outlet opening 57 of the tank reduces the ordinary whirring noise of a tank type suction cleaner.

If the outlet opening 67 is a mere circular opening in the flange 66 with a sharp edge, a whistling noise is produced, which is eliminated by the provision of the interiorly convexly curved shoulder 69 of the second neck 68.

By making the minimum outlet area 70 of the construction 64 at least equal to the minimum preceding opening through which the air passes in the cleaner 11, or in other words, equal to the smallest of the air passage openings in the cleaner, the setting up of back pressure and a reduction in efficiency is avoided.

If the neck 65 is not desired for the reception of a hose coupling, the same may be eliminated and the cap wall 22a merged directly into stop flange 66.

The embodiments of the present improvements illustrated and described herein are by way of example, and the scope of the present invention is not limited to the same or to the particular details thereof, but is commensurate with the subject matter of the following claim, the elements of the claim being intended to include their reasonable equivalents.

I claim:

10 Outlet construction for the outlet end of a tank type suction cleaner provided with a series of air passage openings of various sized areas including, a first tubular outlet neck having its inner end connecting and communicating with the outlet end of the tank, an air stop flange extending radially inwardly from the outer end of the first tubular neck, the stop flange having a central opening of an area reduced with respect to the area of the outlet end of the tank, and a 15 second tubular outlet neck having its inner end connected and communicating with the reduced opening of the flange, the second tubular neck having a wall which is internally convexly curved outwardly and forming an interiorly convexly 20 curved annular shoulder between the stop flange and the other extremity opening of the second neck, and the minimum area of the opening of the second neck being equal to the area of the smallest of said air passage openings of various 25 sized areas in the cleaner.

ELMER J. KASPER.
